York, N. Y., a corporation of Delaware

Application October 30, 1945, Serial No. 625,649

20 Claims. (Cl. 179—15)

1

This invention relates to a multichannel communication system for transmitting and receiving a signal modulated complex pulse wave. More particularly, it deals with the method and means for multiplexing trains of complex pulses to form a complex pulse wave in which both a leading edge and a trailing edge of each complex pulse is time modulated according to different signals.

It is an object of this invention to produce a complex signal modulated pulse and to multiplex such pulses on a complex pulse wave in an effective manner.

Another object is to transmit and receive such a multiplexed complex pulse wave.

Another object is to multiplex trains of such complex pulses vertically by stacking two or more trains of them on top of each other to produce a single train of step shaped pulses.

Another object is to horizontally multiplex trains of such complex pulses by interleaving said trains to produce a single train of complex pulses.

Another object is to both vertically and horizontally multiplex trains of such complex pulses to produce a single train of step shaped complex pulses.

Another object is to separate and demodulate such multiplexed pulse waves.

Another object is to time modulate different signals on the edges of each complex pulse.

Another object is to prevent cross-talk between different channels of signal energy modulated on the same complex pulse wave.

Another object is to provide the means for carrying out the objects mentioned above.

Still other objects and features of this invention will appear from time to time in the description which follows:

Generally speaking, this invention comprises the steps of (1) producing a complex pulse wherein its leading edge is modulated according to one signal and its trailing edge is modulated according to a different signal, as described in my copending application, Ser. No. 614,079, filed September 1, 1945, and of (2) vertically, horizontally or vertically and horizontally multiplexing such complex pulses to form a complex pulse wave.

The sources of signal energy which are modulated on the complex pulses may be from code signals, audio signals, video signals, or the like.

The means for producing the trains of complex pulses modulated according to the energy from said signal sources includes a base wave source, such as a sine wave, saw-tooth wave, pulse wave, or the like, having a constant frequency and at

2

least one sloping edge on each pulse or undulation of the wave. This base wave then may be clipped along the sloping edge, its undulations at different levels varying in accordance with the energy in a given signal. The resulting train of pulses clipped from the base wave thus are time modulated in accordance with the energy of said signal. Other trains of pulses, out-of-phase with at least one time modulated edge of any other pulse train, may be produced by clipping the base wave at other levels and/or by delaying the base wave so that a delayed base wave is produced which is out-of-phase with the original base wave and clipping the resulting delayed base wave at the original or at other levels in accordance with the energy from another signal. Two pulse trains having time modulated edges out-of-phase with each other, may be combined to form a new and complex pulse train in which the leading edge of each pulse thereof is time modulated according to one signal and the trailing edge of each pulse thereof is time modulated according to another signal channel.

Two or more trains of these new complex pulses are then multiplexed to form a single complex pulse wave. The multiplexing of trains of these complex pulses, may be (1) by vertically stacking one or more pulses from different pulse trains to produce a step shaped pulse (each one of the complex pulses having a different width to permit such stacking); or (2) by horizontally interleaving groups of two or more complex pulse trains the number being dependent upon the duration of the complex pulse; or (3) by both vertically and horizontally multiplexing trains of such complex pulses. In order to facilitate modulation and separation of horizontal multiplexed pulse trains, a synchronizing pulse may be interleaved between the complex pulses at regular intervals, such as between each similar group of different signal channels.

The resulting complex pulse wave, having complex pulses multiplexed thereon, may be transmitted and received by any suitable high frequency means such as by radio, by wires or the like. The received multiplexed complex pulse wave is then separated into pulse trains corresponding to each signal channel transmitted on the complex pulse wave. The thus separated pulse trains are separately time demodulated. Horizontally multiplexed pulses may be separated by providing a blocking wave to select only those complex pulses from a given train or group of signal channels. The thus separated complex pulse train is then further separated into pulse

trains corresponding to each signal channel thereon, either by clipping means (if the complex pulse is also vertically multiplexed) and/or by differentiating means to separate the leading edges from the trailing edges of each complex pulse. If desired, when the complex pulse wave contains both horizontally and vertically multiplexed pulse trains, the vertically multiplexed, or step shaped pulses, may first be separated by clipping means before being horizontally separated by a suitable blocking wave.

These and other features and objects of the invention will become more apparent upon consideration of the following detailed description of several embodiments of the invention to be read in connection with the accompanying drawings in which:

Fig. 14 is a graph of wave forms useful in describing the operation of the system of Fig. 13.

The following description is divided into three chapters: Chapter I, illustrated in Figs. 1-6, discloses a vertical multiplexing system; Chapter II, illustrated in Figs. 7-10, discloses a horizontal multiplexing system; and Chapter III, illustrated in Figs. 11-14, discloses a vertical and horizontal multiplexing system.

CHAPTER I

Vertical multiplexing system

Referring to Figs. 1 and 2, there is shown a base wave generator 1 for producing a base wave such as the sine wave 2, which is connected through lines 3 to a modulator clipper 4 which clips a segment 5 out of a sine wave 2 between limits 6 in accordance with the energy in the signal *a* introduced through the line 7 into the

modulator clipper 4. The clipped segment producing the pulse train 8 is then passed through line 9 to the differentiator clipper 10 and thence to the mixer 11. The details of the modulator clipper 4 and differentiator clipper 10 are shown in connection with the circuit for modulating signal *b* below. Since the base wave 2 is clipped along its sloping edge at different levels corresponding to the energy in signal *a*, the edges of the pulses 12 on pulse train 8 vary toward and away from each other in accordance with the signal energy *a*, i. e., the edges of the pulses 12 are time modulated according to the energy in signal *a*.

15 Since the pulses multiplexed in the system of this invention are complex, i. e., having a different signal modulated on the leading edge from that of the trailing edge, only one edge of the pulse 12 is needed in producing the complex pulse.

20 Therefore, the leading edge of pulse 12 is separated from the trailing edge thereof, by differentiating the pulse train 8 to produce the differentiated pulse train 13 wherein only the leading edges of the pulses 12 appear as positive pulses

25 14. These pulses 14 are removed from the rest of the train 13 by clipping it along the line 15. To prevent overlapping of the pulses of one signal with those of another, the clipping level limits 6 of the different signals may be varied within, 30 different voltage ranges along the sloping edge of the wave, as shown and described later in Fig. 4 or the phase of the base wave may be changed and the clipping may take pulses at the same levels 6 as shown in Fig. 2.

35 For producing the edge pulse time modulated in accordance with the signal *b*, the base wave from the generator 1 is passed through line 16 to the delay mechanism, such as the phase shifter 17 comprising a condenser 18 or a variable resistor 19, to produce the delayed base wave 20 shown in dotted lines in Fig. 2. Although the wave 20 is shown delayed an amount so that the leading edge of a pulse train clipped therefrom is in synchronism with the trailing edge of the pulse train

40 of the original base wave no overlap occurs because only the leading edges of each clipped pulse train are used. Such a delay, however, is not necessary provided there is no overlap between the time modulated signal channels of the different signals *a* and *b*. The delayed base wave 20 then passes through line 21 into the modulator clipper 22 which may comprise a double diode 23 and an audio frequency transformer 24. The signal *b* is then connected to transformer 24 through line 25 and its energy varies the level of the clipping segment 5 between the limits 6. The width of the segment 5 is determined by the adjustment of the variable resistors 26 and 27. From the

50 plate 28 of the tube 23 is withdrawn the clipped pulse train 29 having pulses 29a with leading and trailing edges time modulated in accordance with the signal *b*. This pulse train 29 then passes through line 30 to a differentiator clipper 31, which may comprise a differentiator circuit consisting of condenser 32 and resistor 33, for producing the differentiated pulse train 34. Differentiated pulse train 34 is then passed on to one of the grids of the clipper tube 35 which is biased through the resistor 33 so as to pass only the positive pulses 36 of the differentiated pulse trains 34 by clipping them off along the line 37. These positive pulses 36 are then withdrawn from the plate of tube 35 through the line 38 into the

The mixer 11 may comprise two triodes 39, the grids of which are coupled in parallel with the lines from the differentiator clippers 10 and 31. These triodes 39 prevent energy in the pulses of one differentiator clipper circuit from feeding back into the circuit of the other differentiator clipper. From the plates of the triodes 39 is withdrawn a combined complex pulse train 40 through line 41. The odd numbered pulses on this train 40 corresponding to the time modulated signal channel *a* and the even numbered pulses correspond to time modulated signal channel *b*. In order to combine these two pulses into a single wider complex pulse, the train 40 is passed to a trigger circuit 42 from which is withdrawn the complex pulse train 43 through line 44. The trigger circuit 42 may comprise a pair of triodes 45 coupled in such a manner that an odd numbered pulse causes one of the tubes to fire an even numbered pulse fires the other tube which then remains conductive until the next odd numbered pulse fires the first tube again, and so on. Thus, this circuit produces the complex wave 43, which then is passed through line 44 to the mixer 46.

Signals *c* and *d* may be similarly modulated on further delayed base waves 47 and 48 respectively, produced from the base wave 2 in phase shifters 49 and 50 connected to generator 1 through line 16. These delayed waves 47 and 48 are modulated and clipped in circuits 51 and 52 (similar to circuit 22) from the energy of signals *c* and *d* introduced through lines 53 and 54, respectively. From the modulator clippers 51 and 52 are withdrawn pulse trains 55 and 56 which are separately differentiated and clipped in circuits 57 and 58 (similar to differentiator clipper circuit 31) to produce trains of positive pulses 59 and 60, respectively. These pulses 59 and 60 are mixed in a mixer 61 to produce the pulse train 62 which is passed to a trigger circuit 63 (similar to 42) to produce the complex pulse train 64 which passes to the mixer 46 (similar to the mixer 11). From the mixer 46 is withdrawn a vertically multiplexed complex step shaped pulse wave 65 through line 66 for transmission by a suitable ultra high frequency apparatus.

In order to vertically stack the complex pulses produced on wave trains 43 and 64, it is necessary that the basic width of the pulses in each train be different. However, if the pulses had the same width and were sufficiently out-of-phase with each other to partially overlap a complex step pulse could be formed wherein the leading edge of one pulse train would be on the leading edge of the first step of the step shaped pulse, and the trailing edge of that pulse on the same pulse train would be on the trailing edge of the second step of the step shaped pulse, and correspondingly the leading edge of each pulse of the second pulse train would be the leading edge on the second step of the step shaped pulse and the trailing edge of that pulse on the same second pulse train would be the trailing edge of the first step of the step shaped pulse. Complex step shaped pulses of this type may be employed in scrambling signal channels for secrecy.

Another system for producing trains of complex pulses and vertically modulating them on a complex wave similar to wave 65 is disclosed in Figs. 3 and 4, wherein 67 is a pulse generator producing a pulse wave 68 which is transmitted through line 69 to leading edge and trailing edge wave shapers 70 and 71 respectively. These shapers produce waves having sloping edges which may be modu-

lator clipped to form pulse trains having timed modulated pulses.

Leading edge wave shaper 70 produces from the base pulse wave 68 inverted wave 72 having pulses or undulations with a leading sloping edge 73 through the means of a tube 74 and condenser 75. The shaped base wave 72 is then connected through line 76 to a network of modulator clippers 77, 78 and 79 (similar to modulator clipper 22 shown in Fig. 1) wherein the wave 72 is modulator clipped at the different channel levels shown in Fig. 4 to produce pulse trains having time modulated leading edges only (since trailing edge 81 is vertical) corresponding to the energy in signals *a*, *b* and *c*, respectively. The resulting pulse trains (not shown) are separately passed to the mixer 80 (similar to mixer 11 shown in Fig. 1).

The trailing edge wave shaper 71 comprises a delay device 83, a phase inverter 84, and a differentiator clipper 85. The delay device 83 may comprise a network of inductances and condensers to assimilate the transmission line. The phase inverter 84 may comprise a triode 86, from the plate of which is withdrawn the delayed and inverted pulse wave 87 through line 88. This wave 87 is then passed to the differentiator clipper 85 (similar to 31 shown in Fig. 1 without transformer 24) contains circuit elements of sufficient magnitude to produce a wave of the form 89. Wave 89 is then clipped along the line 90 in the tube 85a to produce a second shaped base wave of positive undulations having vertical leading edges 91, in exact alignment and synchronism with the trailing edge 81 of wave 72, and having a sloping trailing edge 92 complementary to the edge 73 of wave 72. Since the tube 85a inverts the wave 89, a phase inverter 84a similar to 84 is required to produce the positive undulations of wave 89. These positive undulations are then passed through line 93 to the modulator clippers 94, 95 and 96 and clipped at the different channel levels shown in Fig. 4 to produce pulse trains (not shown) corresponding, respectively, to signals *d*, *e* and *f* introduced into these modulator clippers, (also similar to the modulator clipper 22). The separate pulse trains are then passed into the mixer 80 from which is withdrawn, through line 97 for transmission, a vertically multiplexed complex step shaped pulse wave 98 similar to the wave 65.

In Figs. 5 and 6 is shown a system for separating and demodulating a vertically multiplexed complex step shaped pulse wave of the type produced in the system of Fig. 1 or 3. Such a complex wave is shown again in Fig. 6 at 99, which is received over line 100 in Fig. 5 and coupled to the separate channel clippers 101, 102, and 103.

The channel clippers 101, 102 and 103 may be similar to the double clipper circuit 22 shown in Fig. 1 without the transformer 24 therein. A schematic wiring diagram of such a double clipper is disclosed later in Fig. 13. These channel clippers clip off the different steps of the complex pulses on wave 99 as shown between the horizontal lines in Fig. 6. Since both the leading edge and the trailing edge of each step carries a different signal channel, each clipped step comprises a complex pulse train (such as train 104 for signal channels *a* and *b*) wherein each pulse carries two signal channels. The complex pulse trains from the clippers 101, 102 and 103 are then respectively passed to the differentiators 105, 106, and 107 to separate the leading from the trailing edges of each pulse on the pulse trains. For example, the differentiated pulse train from pulse train 104 is

shown at 108. The differentiated pulse trains are then clipped to remove the positive pulses corresponding to signal channel *a*, *c* and *e* in clippers 109, 110 and 111, respectively. To separate the edge pulses of channels *b*, *d* and *f*, respectively, the differentiated trains from 105, 106 and 107, are passed through the phase inverters 112, 113 and 114 to produce an inverted train (similar to 115 which corresponds to channel *b*) which trains are then clipped in clippers 116, 117, 118. (The clipped time modulated pulse channels for signals *a* and *b* are shown by waves 119 and 120 respectively.) The separated pulse train channels are then each separately demodulated in the pulse time demodulators 121, 122, 123, 124, 125 and 126 from which are withdrawn reproduced signals *a*, *b*, *c*, *d*, *e*, and *f*, respectively. The pulse time demodulators may include a harmonic generator 127 which produces a wave having sloping edges and preferably is a harmonic of the original base wave 61 produced in the system of Fig. 1 or 3. The addition of a pulse channel train to the sloping edges of such a harmonic wave, produces amplitude modulated pulses on the wave, which may be clipped off in tube 128 and passed through the low pass filter 129 from which is withdrawn the desired signal, which in this case is *a*. More details of such a time demodulator are disclosed in my copending application Serial No. 459,959, filed September 28, 1942, U. S. Patent No. 2,416,306, granted Feb. 25, 1947.

CHAPTER II

Horizontal multiplexing system

In Figs. 7 and 8 is shown a system for horizontally multiplexing a series of complex pulses in which each pulse has one signal modulated on its leading edge and another signal modulated on its trailing edge. This system comprises a base wave generator 130 for producing the wave 131 which passes through line 132 into a double clipper 133 (similar to that shown in Fig. 13 described later) which cuts the top off of the undulations of wave 131, to produce a train of synchronizing pulses 134 that are passed through line 135 to the mixer 136.

The signals to be transmitted are modulated from different delayed base waves out-of-phase with the wave 131. These different delayed base waves are produced from the series of delay devices 137, 138, 139, 140, 141, 142 and are shown in dotted lines in Fig. 8 at 143, 144, 145, 146, 147 and 148, respectively. The base waves are then modulator clipped, respectively according to signals *a*, *b*, *c*, *d*, *e* and *f* in modulator clippers 149, 150, 151, 152, 153, 154, to produce a series of pulse trains similar to those for signal channels *a* and *b* shown in Fig. 8 as trains 155 and 156. Since the next complex pulse train is composed of pulses corresponding only to the leading edges of the pulses on trains 155 and 156 these trains are differentiated to form trains 155a and 156a and then clipped to remove only their positive pulses in the first two of the differentiator clippers 157, 158, 159, 160, 161, 162, respectively. The resulting positive pulse trains from the clippers 157 and 158 are then mixed in mixer 163 (similar to mixer 11 in Fig. 1) from which is withdrawn the pulse train 164 which is then passed into trigger circuit 165 (similar to trigger circuit 142 in Fig. 11) to produce the complex pulse train 166 which is passed to the mixer 136. Likewise the pulse trains of signal channels *c* and *d* are mixed in mixer 167, triggered in circuit 168, and passed to

mixer 136, and similarly pulse trains of signal channels *e* and *f* are mixed in mixer 169, triggered in circuit 170, and passed to mixer 136. From mixer 136 through line 171 is withdrawn the horizontal multiplexed complex pulse wave 172, having synchronizing pulses *S* interleaved between each similar group of different complex pulse channels. If desired, further signal channels, besides the six shown, may be produced and interleaved between the synchronizing pulses *S*. Such additional circuits would be connected to other delay devices through line 174 and to the mixer 136 through line 175.

Figs. 9 and 10 disclose a system for separating and demodulating the signals on a horizontally multiplexed complex pulse wave of the type of 172. Such a wave is received through line 176 and connected to the pulse width selector 177 and the complex pulse train selectors 178, 179, 180.

The pulse width selector 177 (similar to that disclosed in my copending joint application Ser. No. 487,072, filed May 15, 1943, U. S. Patent No. 2,440,278, granted April 27, 1948) separates the synchronizing pulses *S* on wave 172 from the wider time modulated complex pulses carrying the signal channels. This pulse width selector may comprise an amplifying tube 181 for amplifying the current of the pulse wave 172, which is then passed into the time constant circuit 182 tuned to be responsive to the width of the synchronizing pulses *S*. The undulations of the time constant circuit 182 are damped through damping tube 183 so that only the first undulations having the greatest amplitudes are clipped in clipper circuit of tube 184 to produce the synchronizing wave 185. From this wave 185 is then produced a blocking wave 186 in the multivibrator 187. The circuit of the multivibrator 187 may comprise two tubes 188 and two time constant circuits, comprising: (1) variable resistor 189 and condenser 190 and (2) variable resistor 191 and condenser 192. These latter time constant circuits are adjusted so that the pulses on wave 185 fires one of the tubes 188 which remains conductive for a time sufficient to completely block any one of the signal modulated pulses on wave 172, and then the other tube 188 is fired and remains conductive until the next pulse on wave 185 fires the first tube again. This block wave 186 is then withdrawn through line 193 and connected to the series of delay mechanisms 194, 195 and 196, for delaying the wave 186 so it will be in synchronism with each different train of complex pulses on wave 172.

The resulting delayed blocking waves withdrawn from the delay devices are then respectively coupled to pulse train selectors 178, 179 and 180, each of which may comprise a mixer clipper circuit. The mixer clipper circuit may comprise two triodes 197, the grids of which are connected respectively to the delayed blocking wave and to the complex pulse wave. Each one of these tubes are biased sufficiently so that the composite wave 198 will be clipped along the line 199 to remove only the desired train of signal pulses.

This selected complex pulse train is then withdrawn through line 200 and passed through the differentiator 201 to produce the differentiated pulse train 202 which differentiated pulse train is both (a) clipped along line 203 and (b) inverted (to produce wave 204) and clipped along line 205, to separate signal channels *a* and *b* respectively carried on the leading and trailing edges of each pulse of the selected complex pulse train. The resulting separated signal channels are pulse time

demodulated to reproduce the signals *a* and *b* withdrawn through lines 206 and 207, respectively. This circuit 208 from pulse train selector 178 is the same as that disclosed for the separation and demodulation of the complex pulses described in Fig. 5 above and will be referred to hereinafter as a channel separator and demodulator circuit.

The other complex pulse trains are similarly separated in the pulse selectors 179, 180 and the channels thereon are separated and demodulated in the channel separator and demodulator circuits 209, 219 (similar to circuit 205) from which are withdrawn signals *c*, *d*, *e*, and *f* through lines 211, 212, 213, 214, respectively. Other pulse trains may be selected in a similar manner and connected to lines 215, and 216 carrying the received complex pulse wave and the blocking wave, respectively.

CHAPTER III

Vertical and horizontal multiplexing

The vertically multiplexed step shaped complex pulses produced by the systems disclosed in Chapter I may also be horizontally multiplexed according to the system disclosed in Chapter II. In Figs. 11 and 12 there is shown such a system comprising a base wave generator 217 for generating the wave 218 which is connected through line 219 to the group I vertical multiplexing circuits 220 for producing a vertically multiplexed pulse wave 221 containing signal channels *a*, *b*, *c*, *d*, etc., which is withdrawn through the line 222 and to a mixer 223 (similar to 11 in Fig. 1). The vertical multiplexing circuits may be similar to those disclosed in Fig. 1 or Fig. 3 above. The wave 218 is also passed through line 224 to a suitable delay device 225 from which is withdrawn the delayed base wave 226, which is then connected to group II vertical multiplexing circuits 227 from which is withdrawn a vertically multiplexed pulse wave 228 which is passed through line 229 of the mixer 223. Still other delay devices and vertical multiplexing circuits may be connected to line 230 to produce other group pulse waves which are then connected to the mixer 223. From mixer 223 is withdrawn the resulting vertically and horizontally multiplexed complex pulse wave 231, through line 232 for transmission.

In Figs. 13 and 14 is shown a system for separating the channels on a complex pulse wave of the type shown at 231. Such a wave is passed through line 232 and connected both to a blocking wave circuit 233 and to groups I, II and III, etc., separator circuits 234, 235, 236, etc. This system does not disclose the use of a synchronizing pulse for separating similar groups of complex pulses as described in the system of Chapter II, but instead discloses a circuit whereby a blocking wave may be produced directly from the complex pulses on the wave 231.

The blocking wave circuit 233 consists of a high-“Q”-circuit 237, a variable sine wave phaser 238, a double clipper 239, a differentiator 240, and a multivibrator circuit 241. The high-“Q”-circuit 237 may comprise a tube 242 and a time constant circuit 243 for smoothing out the sharp corners on the wave 231 and produce a sine wave which is withdrawn through line 244 into the variable sine wave phaser 238 consisting of a condenser 245 and a variable resistor 246. The variable sine wave phaser is so adjusted that the leading edge of each positive undulation on the waves 247 and 250 are in synchronism with the

center of the spaces 255 between the complex pulses on the wave 231. From the sine wave phaser 238 is withdrawn the delayed sine wave 247 through line 248 into the double clipper circuit 239, similar to clipper modulator circuit 22 shown in Fig. 1 but without the transformer 24. In circuit 239, the double diode 249 also may act as an amplifier as well as a clipper for clipping off the round ends of the wave 247 and thereby produce the rectangular shaped wave 250 which is withdrawn from the plate 251 of tube 249 through line 252. The resistors 253 and 254 may be adjusted and biased to aid in shaping the square wave 250. The wave 250 is then passed to the differentiator circuit 240 from which is withdrawn the pulse wave 256. This pulse wave is then passed into the multivibrator circuit 241 to produce the blocking wave 257. This multivibrator circuit is similar to the multivibrator circuit 187 shown in Fig. 9, the resistors 258 and 259 in the time constant circuits thereof being so adjusted as to provide pulses 260 on wave 257 of sufficient duration to reach from one space 255 to the next adjacent space 255 of the same frequency as a given group complex vertically multiplexed pulse train interleaved on the wave 231. The blocking wave 257 is then passed through line 261 into a group I separator circuit 234 which in this case comprises a mixer clipper similar to that disclosed at 178 in Fig. 9. In the mixer clipper the wave 262 is produced and clipped along the line 263 to separate the complex vertically multiplexed pulses 264 of group I. These pulses 264 are then passed through line 265 to the group I channel separator and demodulator circuits 266 similar to those previously described and from which are withdrawn the reproduced signals *a*, *b*, *c*, *d*, etc.

The group II separator circuits 235 comprises, in addition to a mixer clipper 267, a delay device 268 for delaying the blocking wave 267 to produce the delayed blocking wave 269. This delayed wave 269 is mixed in the mixer clipper 267 to produce the wave 270 which is clipped along the line 271. The resulting clipped pulses 272 are then passed through line 273 to the group II channel separator and demodulator circuits 274 which may be similar to those of 266 and from which are withdrawn the reproduced signals *e*, *f*, *g*, *h*, etc.

Group III separator 236 is similar to the group II separator 235 and the group III channel separator and demodulator circuits 275 are similar to those of group I at 266 or group II at 274. Still further, group separator and demodulator circuits may be connected to the lines 276 and 277, if desired.

The foregoing systems may be extended to multiplex channels other than those specifically shown, provided a sufficient free space is maintained between each of the signal channels to avoid cross talk from one signal channel to the other. This applies both to the vertical multiplexing and to horizontal multiplexing of the time modulated edges of the complex pulses produced by the systems of this invention and my copending application, Serial No. 614,079, filed September 1, 1945.

While the principles of the invention have been described in connection with several specific systems it is to be clearly understood that these descriptions are made only by way of example and not as a limitation on the scope of the invention as defined in the objects and the accompanying claims.

I claim:

1. In a multichannel system means to produce a pulse having vertically disposed portions of different widths and means to time modulate the leading edge with one signal and the trailing edge with another signal of each such portions.

2. A system for multiplexing signal modulated pulses to produce a complex pulse wave wherein each pulse carries one time modulated signal on a leading edge thereof and another time modulated signal on the trailing edge thereof comprising: at least two sources of signal energy, means to produce a plurality of pulse trains respectively time modulated with energy from said signal sources, said pulses being out-of-phase with each other, means to combine two pulses from different pulse trains to form a single new pulse train, and means to multiplex a plurality of said new pulse trains to produce said complex pulse wave.

3. The system of claim 2 wherein the means for multiplexing includes means to superimpose the pulses of said new pulse trains to produce a step shaped pulse on said complex pulse wave.

4. The system of claim 2 wherein the means for multiplexing includes means to interleave the pulses of said new pulse trains on said complex pulse wave.

5. The system of claim 2 wherein the means for multiplexing includes means to superimpose the pulses of said new pulse trains to produce step shaped pulses and means to interleave said step shaped pulses on said complex pulse wave.

6. The system of claim 2 wherein said means for producing a plurality of pulse trains includes means to produce a base wave having a sloping edge, and means to clip said base wave along said sloping edge at various levels corresponding to the energy from said signal sources.

7. The system of claim 2 wherein the means for producing a plurality of pulse trains includes a base wave source, and means to produce two similar waves, out-of-phase with each other, from said base wave.

8. A system for multiplexing signal modulated pulses to produce a complex pulse wave wherein each pulse carries one time modulated signal on a leading edge thereof and another time modulated signal on the trailing edge thereof comprising: at least two sources of signal energy, a base wave source, means to change the phase of said base wave, means to produce pulse trains from the original base wave and the base waves out-of-phase with the original base wave, means for respectively modulating the pulses of said trains with energy from said signal sources, means to interleave the pulses of said pulse trains to produce a new pulse wave means to combine successive pairs of pulses on said new pulse wave to form a series of single pulses each bearing two modulated signal channels, and means to multiplex a plurality of the resulting new pulse waves to produce said complex pulse wave.

9. The system of claim 8 wherein said means to combine successive series of pulses comprises a trigger circuit means.

10. The system of claim 8 wherein said means to produce one of said pulse trains includes a differentiating means and a clipping means.

11. A system for multiplexing signal modulated pulses to produce a complex pulse wave wherein each pulse carries one time modulated signal on a leading edge thereof and another time modulated signal on the trailing edge thereof comprising: at least two sources of signal energy,

means to produce a plurality of pulse trains respectively time modulated at one edge per pulse with energy from said signal sources, means controlling said pulse trains so that the unmodulated edges of corresponding pulses of said pulse trains coincide, means to combine corresponding pulses from each train into a single pulse on a new pulse train, and means to multiplex a plurality of said new pulse trains to produce said complex pulse wave.

12. The system of claim 11 wherein said means to produce a plurality of pulse trains includes a base wave source, means for separating said base wave to produce two base pulse waves one of which has pulses with a sloping leading edge and the other of which has pulses with a sloping trailing edge, said base pulse waves being out-of-phase with each other.

13. A communication system for transmitting and receiving a complex pulse wave having more than two signal channels modulated thereon comprising: more than two sources of signal energy, means to produce a plurality of pulse trains respectively time modulated with energy from said signal sources, said pulses being out-of-phase with each other, means to interleave the pulses of said pulse trains to produce a new pulse wave, means to combine successive pairs of pulses in said new pulse waves to form a series of single pulses each bearing two signals, means to multiplex a plurality of the resulting combining pulse waves to produce a complex pulse wave wherein each pulse carries at least one time modulated signal in a leading edge thereof and another time modulated signal on the trailing edge thereof, means to transmit said complex pulse wave, means to receive the complex pulse wave, means to separate said complex pulse wave into pulse trains corresponding to each of said signals modulated thereon, and means for demodulating each of said pulse trains.

14. The system of claim 13 wherein said means for multiplexing includes means to superimpose the pulses of said new pulse trains to produce a step shaped pulse on said complex pulse wave.

15. The system of claim 13 wherein the means for multiplexing includes means to interleave the pulses of said new pulse train on said complex pulse wave.

16. The system of claim 13, wherein said means for multiplexing includes means to superimpose the pulses of said new pulse trains to produce step shaped pulses and means to interleave said step shaped pulses on said complex pulse wave.

17. A communicating system for transmitting and receiving a complex pulse wave having horizontally multiplexed pulses thereon wherein each of said pulses carries one time modulated signal on a leading edge thereof and another time modulated signal on the trailing edge thereof, comprising: more than two sources of signal energy, a base wave source, means controlled by said base wave to produce a synchronizing pulse, means controlled by said base wave to produce a plurality of pulse trains respectively time modulated with energy from said signals, all the edges of said pulses produced from said base wave being out-of-phase with each other, means to combine two pulses from different pulse trains to form a single new pulse train, means to horizontally multiplex a plurality of said new pulse trains to produce a complex pulse wave having a synchronizing pulse interleaved at regular intervals between the complex pulses thereon,

13

means to transmit said complex pulse wave, means to receive said complex pulse wave, means to separate the signals modulated on said complex pulse wave comprising a blocking wave controlled by the synchronizing pulse on said complex pulse wave, means for separating the signal channels on the separated pulses to produce pulse trains corresponding to each signal carried by said complex pulse wave, and separate means to demodulate each of said separated pulse trains.

18. A method of communicating a complex pulse wave carrying a plurality of multiplexed time modulated signals, wherein each pulse on said wave carries one time modulated signal on a leading edge thereof and another time modulated signal on the trailing edge thereof comprising: producing a plurality of pulse trains respectively time modulated with energy from said signals, said pulses being out-of-phase with each other, combining two pulses from different pulse trains to form a single new pulse train, multiplexing a plurality of said new pulse trains to produce said complex pulse wave, transmitting said complex pulse wave, receiving said complex pulse wave separating the signals on said received complex pulse wave into separate pulse trains corresponding to each of said signals, and separately demodulating said separated pulse trains to reproduce said signals.

19. In a communication system for receiving a complex pulse wave having multiplexed complex pulses thereon, said complex pulses having one time modulated signal on a leading edge thereof and another time modulated signal on the trailing edge thereof, said complex pulses being horizontally multiplexed in an interleaved manner, means for separating the wave into pulse trains corresponding to each signal modu-

14

lated on said complex wave, said separating means including means for producing a blocking wave having the same frequency as a given train of complex pulses to separate a given pair of signal channels, and means for separating said separated pairs of signals comprising differentiating means, and means for demodulating each of said separated pairs of signals.

10 20. In a communication system for receiving a complex pulse wave having multiplexed complex pulses thereon, said complex pulses having one time modulated signal on a leading edge thereof and another time modulated signal on the trailing edge thereof, said complex pulses being both vertically and horizontally multiplexed on said complex pulse wave, means for separating the wave into pulse trains corresponding to each signal modulated on said complex wave, said separating means including a blocking wave for separating the horizontally multiplexed complex pulses, a clipping means for separating the vertically multiplexed pulses, and a differentiating means for separating the leading edge from the trailing edge of the pulses of the resulting separated pulse train to thereby separate the signal channels, and means for demodulating each of said separated edges to reproduce the signal.

DONALD D. GRIEG.
